UNITED STATES PATENT OFFICE.

BENJAMIN F. LADUE, OF RAYMOND, WASHINGTON.

COMBINED STORM SASH AND WINDOW SCREEN.

Application filed July 25, 1921. Serial No. 487,253.

To all whom it may concern:

Be it known that I, BENJAMIN F. LADUE, a citizen of the United States, and a resident of Raymond, in the county of Pacific 5 and State of Washington, have made certain new and useful Improvements in Combined Storm Sashes and Window Screens, of which the following is a specification.

This invention relates to a combined 10 storm sash and window screen.

As is well known, when a rain storm occurs it is usually the practice during the summer months when a house is fully screened, to remove the screens from the 15 lower windows, if they should be of the folding type, and to close the lower windows in order to keep out the rain.

In such cases the house becomes uncomfortably warm during the rain storm, and 20 with this in mind it is the object of the present invention to combine with a window screen a storm sash which will prevent the rain coming through the screen and thus enable the windows to be always 25 open and screened during a storm.

It is also an object of the invention that the combined storm sash and screen be adapted to be easily and quickly positioned 30 in the runway of the lower window sash.

It is a further object of the invention to associate means with the present invention whereby the flapping of curtains usually associated with windows during a storm 35 will be substantially eliminated.

Other objects will hereinafter appear.

The invention is illustrated by way of example in the accompanying drawing, in which:

40 Figure 1 is a front elevation of the combined storm sash and screen.

Figure 2 is an end elevation of the same, showing the flap associated therewith in position for shortening the storm sash in 45 order that it may be inserted in the guideways of a window sash.

Figure 3 is a vertical sectional view of the same.

Figure 4 is a top plan view of the combined storm sash and screen and showing the same positioned in the guideways of a window sash, the guideways being shown in cross section.

Figure 5 is a view similar to Figure 4, 55 but illustrating the combined storm sash

and screen in its position previous to being inserted in the guideways of the window sash.

Figure 6 is a partial vertical sectional view of the combined storm sash and screen, 60 and particularly illustrating the manner in which the flapping of a curtain associated with the window is eliminated.

Referring to the drawings more particularly, A indicates generally a frame or 65 sash comprising top and bottom members 10 and 11, respectively and side members 12 and 13. The joining edges of the frame members are preferably mortised together as shown in Figures 4 and 5 and between 70 the side members there extends a plurality of slats 14, the upper side surfaces of which are inclined toward the inner longitudinal edges thereof; also the outer longitudinal edges of the slats extend slightly beyond 75 the outer surfaces of the side frame members 12 and 13, as shown. A suitable screen 15 is secured upon the inner side of the frame A to form a closure of the opening 80 formed by said frame. It will be observed that the side frame member 13 is of less width than the same member 12, and upon the outer edge of the side frame member 13 there is hinged a flap 16 by the means of the hinges indicated at 17. The hinges 85 17 are adapted to permit the flap 16 to be swung outwardly as shown in Figures 2 and 5, and when swung inwardly as shown in Figure 4, the inner edge of the flap is adapted to abut the adjacent edge of the 90 side frame member 13. Also the longitudinal edge of the flap 16 is rounded as at 18 for a purpose which will later be made evident.

Referring to Figures 4 and 5, 19 indicates 95 the sides of the window frame casing and 20 the usual strips forming the guideways for the lower window sash.

When it is desired to position the combined storm sash and screen in the runways 100 of the window sash mentioned, the flap 16 is folded back as shown in Fig. 5, whereupon the frame A is of such a width that it may be slid between the guideways of the window sash and then the flap 18 moved to its extended position as shown in Figure 4. The window sash was of course previously raised to permit the insertion of the frame A and now the same may be lowered so that it will rest upon the top member 10 of the 110

frame A, thus forming a tight closure therewith.

For eliminating the flapping of a window curtain during a storm, I provide a pair of 5 spring rods 21, one of the rods being secured at its lower end to the side frame member 13 as at 22, Fig. 2, while the other rod is secured in a similar manner to the side frame member 12. The upper ends of the rods are 10 turned inwardly and have pivoted therebetween a strip 23. When the strip 23 is brought to the position as shown in full lines in Figs. 2. to 5 inclusive, the arm 21 will press the same inwardly against the frame A 15 and the inner edge of the strip will seat upon a molding board as at 27.

As is obvious with this construction, when the air passes between the strips 14 as indicated by the arrows 28, the same will be deflected downwardly by the strip 23 and thereby protect the window curtain, which, as usual, would be above the strip 23.

In case it is not desired to use the curtain protector, that is the strip 23, the same may 25 be moved to the dotted line position shown in Fig. 6. When in this position the spring arms 21 will fold against the side frame members 12 and 13 and as a whole the attachment will present a neat appearance.

I claim:—

1. In combination, a window frame, a pair of spring rods extending outwardly from the window frame, a strip pivotally supported between the outer ends of said spring rods and adapted to be adjusted to 35 extend at an angle with relation to the plane in which the window frame is disposed, the inner edge of said strip resting against the window frame and so held by the tension of the spring rods, and said strip being also 40 adapted to be rotated and one of its faces brought to rest against the window frame and held in this position by the spring rods.

2. In combination, a window ventilating frame, a strip positioned upon the inner side 45 of the frame parallel with the upper edge thereof, and spring means carried by said frame supporting said strip whereby the strip may be adjusted to extend at an angle with relation to the vertical plane in which the window frame is disposed and thereby to direct downwardly any current of air entering said window frame, said supporting means being also adapted to permit folding 50 of the strip against the window and so hold the same in its inoperative position by the spring action thereof.

BENJAMIN F. LADUE.
